UNITED STATES PATENT OFFICE.

FREDERICK ENGELHARDT, OF NEW YORK, N. Y.

PIANO-ACTION.

SPECIFICATION forming part of Letters Patent No. 325,401, dated September 1, 1885.

Application filed March 9, 1885. (No model.)

To all whom it may concern:

Be it known that I, FREDERICK ENGELHARDT, of the city of New York, in the county of New York and State of New York, have 5 invented a new and Improved Piano-Action, of which the following specification is a full, clear, and exact description.

This invention relates to an improvement in piano-actions, and refers more particularly 10 to the butt-flange of upright pianos.

The invention consists in the elements of improvement hereinafter more fully pointed out.

In the accompanying drawings, Figure 1 is 15 a longitudinal vertical section of a piano-action embodying my invention. Fig. 2 is a top view of my improved butt-flange, showing it connected to the hammer-butt and the damper. Fig. 3 is a side view of Fig. 2.

20 The letter *a* represents the key of a piano, *b* is the bottom rail, *c* the jack, *d* the hammer-butt, *e* the action-rail, and *f* the damper, all as usual. The damper carries the butt-flange *g*, to the forward end of which the hammer-butt 25 is pivoted. Around this pivot the hammer-butt oscillates as the piano is played. The butt flange *g* is made of metal, and is of the form shown in Fig. 2—that is to say, it is made in the form of a square plate provided with 30 two projections, *h h*, at its rear end to straddle the damper *f*, to which it is pivotally connected. At the front the plate *g* is cut away at the top to form a step, *i*, against which there is placed a small rigid binding-plate, *j*. This 35 plate extends forward to the front edge of plate *g*.

Beneath plate *j* the plate *g* is provided with a transverse groove, *k*, to receive a pivot-pin,

l. This pin, which is the pivot-pin of the hammer-butt, is introduced with its ends into two 40 cheek-pieces, *m m*, of the hammer-butt *d*, forming a slot between them, Fig. 2. The pivot is clasped between plates *g j* by means of a screw, *n*, which connects said plates. The pin *l* is permanently attached to the hammer-butt, and 45 in order to connect this butt to the butt-flange the screw *n* is loosened and the pin introduced into the groove *k*. The screw *n* is then tightened up, and the pin is thus locked in position. In order to facilitate the introduction 50 of pin *l* between plates *g j*, I prefer to bevel the front edge of the plate *j*, as shown in Figs. 1 and 3.

The drawings show the invention applied to an action known as an "American-style action." In the French-style action the butt-flange *g* is placed in an upright position, and is attached to the action-rail *e* instead of to the damper *f*. Otherwise the parts remain of the same construction. 60

This invention may also be applied to grand pianos.

I claim as my invention—

1. The combination of hammer-butt *d* and butt-flange *g*, cut away at the top to form step 65 *i*, with rigid plate *j*, fitting against said step and with screw *n*, substantially as specified.

2. The combination of hammer-butt *d* with butt-flange *g*, plate *j*, having beveled front edge, and with screw *n*, substantially as shown 70 and described.

FREDERICK ENGELHARDT.
